BRAIDING MACHINE

Anker Petersen, Boston, Mass., assignor to James Joseph Lannon, West Newton, Mass.

Application October 23, 1936, Serial No. 107,206

18 Claims. (Cl. 96—3)

This invention pertains to braiding machines, relating more particularly to braiding machines of the general type disclosed in the patent to Petersen No. 1,796,938, dated March 17, 1931, 5 wherein a series of bobbin carriers is revolved in a circular path about the axis of the machine while a second set of carriers, disposed in a circle concentric with the first set, either revolves in the opposite direction or remains stationary,— 10 the strands from the latter set of carriers being so controlled that each carrier of the first set passes alternately over and under strands from said second set of carriers.

In the patent to Petersen, No. 2,111,639, granted 15 March 22, 1938, there is disclosed a novel braid comprising flat strands or ribbons of stiff resilient metal interbraided to form a tube and so closely intermeshed as to leave interstices of substantially inappreciable size at the crossings of the constituent strands. One object of the present invention is to provide a machine of commercially practical type capable of making such a braid as 20 that disclosed in the above patent.

A further object is to provide a braiding machine capable of braiding other materials than metallic ribbons, for example, textile strands, in particular heavy strands, for instance ten-cord cotton threads, rope-yarns or the like in such a manner as to make a braid, either with or without 25 a core, wherein the constituent strands are packed more closely and solidly together than has heretofore been considered possible.

In machines designed for making such a close braid as that just referred to, particularly when 30 the strands employed are heavy or otherwise intractable, the problem of driving the carriers at the requisite speed for commercial production and at the necessary uniformity of velocity, but without development of undue friction and demand for excessive power in driving the machine, 35 is exceedingly difficult, and the present invention has for a further object the provision of improved means for supporting, guiding and driving the carriers such that friction is reduced to a minimum, with consequent reduction in power required to drive the apparatus, and whereby great 40 accuracy and uniformity in the driving of the carriers is assured regardless of the weight of the carriers or the tension which it may be necessary 45 to impose upon the individual strands.

In the attempt to interbraid strands to form a firm close braid, devoid of interstices of substantial size, it has heretofore been proposed to employ either a stationary guide ring or cone 50 concentric with the braiding die and over which the

merging strands pass on their way to the braiding point, or to use mechanically actuated beaters for beating up the strands after the manner of the operation of the lay of a loom, but both of such expedients increase the power required 5 and neither, it is believed, is dependable for obtaining the desired results, especially when the strands are of stiff resilient material or otherwise intractable, for example, by reason of size.

After long experiment it has now been discovered that the desired close texture may be obtained without recourse to such prior expedients as above referred to, and that it is possible, by proper relative disposition of the carriers and the braiding die, to deliver the strands directly from 10 the carriers of one set to the braiding point without substantially deflecting them from a straight path and without causing them to contact with or be contacted by interposed mechanical elements, but at the same time to ensure such closeness of 15 texture as has not heretofore been attainable by machine methods of braiding. It is accordingly a 20 further object of the invention to provide a machine embodying such discovery.

In high speed braiding machines such as that 25 to which the present invention is related it is essential, for efficient commercial production, that the machine automatically stop upon exhaustion of strand material from any bobbin of either set, as otherwise defective braid would be 30 produced, the only alternative being constant supervision of each machine, which from the commercial standpoint, is out of the question. Accordingly, a further object of the invention is to provide the machine with automatic stop 35 means which may be depended upon to act promptly whenever the strand is exhausted from any bobbin regardless of the character of the strand employed, but which will not operate until substantially all of the strand of material has 40 been drawn off from the bobbin.

In braiding close textured material such as that above referred to, it is quite essential that the velocity of the take-up of the completed braid be accurately predeterminable with reference to the 45 velocity of revolution of the carriers and also with respect to the size and character of the strand material being used, and with this in view a further object of the invention is to provide improved take-up means which may be driven at 50 an accurate speed ratio with reference to the velocity of revolution of the carriers but with provision whereby said speed ratio may readily be changed at will.

A further object is to provide for accurate ad- 55

justment of the parts and take-up of lost motion between the drive elements for the carriers and to provide improved means for guiding the strands from the second set of carriers so as to 5 reduce friction to a minimum and to ensure a constant tension. A further object is to provide releasable bobbin-retaining means of improved type readily manipulable in introducing or removing a bobbin, but which is dependable to hold 10 the bobbin in place during normal operation of the machine.

Other objects and advantages of the invention will be pointed out in the following more detailed description and by reference to the accompanying drawings wherein:

Fig. 1 is a front elevation of the improved machine, certain parts being broken away and others omitted or indicated in broken lines;

Fig. 2 is a fragmentary plan view, partly in horizontal section, illustrating the relative arrangement of the two sets of carriers and the strand manipulating levers for the upper set of carriers, together with certain elements of the stop mechanism;

Fig. 3 is a fragmentary vertical section with certain parts omitted and others broken away, the section being in a radial plane of the machine, and illustrating the means for supporting and driving the carriers;

Fig. 4 is a side elevation of a bobbin of improved type designed in particular for use with the improved stop mechanism herein disclosed;

Fig. 5 is a fragmentary end elevation of one of the carriers of the upper set, showing certain details of the stop mechanism;

Fig. 6 is a fragmentary diagrammatic plan view, partly in horizontal section and with many parts omitted, but illustrating the arrangement of the carrier drive shafts and the relation of the carriers thereto;

Fig. 7 is a fragmentary side elevation, to larger scale, partly in vertical section, showing a portion of the take-up driving mechanism as viewed from the left-hand side of Fig. 1;

Fig. 8 is a fragmentary elevation, to large scale, showing details of the stop mechanism as viewed from the left-hand side of Fig. 2;

Fig. 9 is an elevation of one of the carriers of the lower set removed from the machine and viewed from its outer end;

Fig. 10 is a fragmentary vertical section generally similar to Fig. 3, but omitting many parts, illustrative of another arrangement for supporting the lower set of carriers; and

Fig. 11 is a view similar to Fig. 10, but showing a further modification.

Referring to the drawings, the numeral 1 designates a base of any appropriate construction, for example, a casting of annular form, preferably having integral legs 2 spaced at suitable distances apart, the base being provided with upwardly directed posts 3 which may be integral with the base, if desired, but which are here shown as separate parts bolted to the base. These posts 3 support a spider 4 (Figs. 1, 2, and 3) having a hub 5 at its center and provided with an annular rim 6 forming a support for a cam ring 7. The cam ring 7 may be secured to the rim 6 of the spider by means of bolts 8 (with interposed shims, if desired) whereby the cam ring may be accurately leveled. This cam ring has an upwardly directed flange 9, preferably inclined to the vertical at an angle of the order of 8°. Its inner peripheral surface is provided 75 with a cam groove 10 for the actuation of the

strand guiding fingers or levers as is common in machines of this general type.

The base member 1 is also provided with posts 11 and 12 which support a transverse rail or bridge member 13 (Fig. 1) which carries a downwardly directed bracket 14 having clamping means 15 at its lower end for fixedly but adjustably positioning a tubular die holder 16 within the lower end of which the braiding die 17 is secured.

Within the hub 5 of the supporting spider is fixedly secured a vertical shaft 18 (Fig. 3) axially aligned with the axis of the braiding die 17 and which, if desired, may be tubular, particularly when the braided material is to include a core 15 strand or the like. This shaft 18 is fixed within the hub 5 of the spider in any suitable way, for example, by splitting the hub and drawing it together about the shaft by means of bolts (not shown), the upper end 19 of the shaft 18 being spaced below the lower end 17 of the braiding die, such lower end of the die substantially defining the braiding point.

The inner element 20 (Fig. 3) of an anti-friction ball bearing rests upon the upper surface 25 of the hub 5 and preferably is splined or otherwise secured to the shaft 18. Above this inner member 20 of the lower ball race is a spacer ring 21 upon which rests the inner element 22 of another anti-friction bearing which in turn supports a spacer sleeve 23 on which rests the inner element 24 of another anti-friction bearing, the members 22 and 24 being likewise splined or otherwise secured to the shaft 18.

The hub 25 of a gear 26 is splined to the outer element 20a of the lower anti-friction bearing and may be adjusted vertically with respect to the member 20a by means of a plate 27 secured to the upper end of the hub and overlying the member 20a—a suitable shim 28 being interposed 40 between the plate 27 and the hub. The gear 26 is furnished with a downwardly directed annular flange 29 to which is bolted the inner edge of an annular gear 30.

The hub 31 of a carrier support 32 is splined to the outer members 22a and 24a of the middle and upper anti-friction bearings above described, being vertically adjustable with respect to said inner bearing elements by means of an overlying plate 33 bolted to the hub, with an adjusting shim 34 interposed between the plate and the hub.

The carrier support 32 is furnished with a peripheral substantially vertical rim or flange 35 having a circumferential groove 36 in its inner surface, said groove opening inwardly toward the axis of the machine. The support 32 also carries a ring 37, preferably adjustable circumferentially as by means of bolts 37a and slots 37b (Fig. 2), and having a rim 38 provided with a circumferential groove 39 in its outer periphery, said groove opening outwardly from the axis of the machine, the grooves 36 and 39 constituting concentric guideways or tracks for the carriers C of the lower set.

The carrier support 32 is also furnished with a downwardly directed annular flange 40 to the lower part of which is secured a second annular gear 41 of the same pitch diameter as the annular gear 30 above described. A pinion 42 meshes with the gear 41, such pinion being mounted upon the upper end of a substantially vertical shaft 43 (Figs. 1 and 3), turning in bearings in the spider 4 and in the base member 1, respectively, and having a sprocket wheel 44 75

fixed to it near its lower end. A sprocket chain 45 engages this sprocket wheel and passes around a second sprocket wheel 46 (Fig. 1) mounted near the lower end of a vertical shaft 47, also 5 turning in suitable bearings in the spider 4 and base member 1, said shaft having fixed to it a gear 52 which meshes with the annular gear 30. A pulley 48 is secured to the shaft 47 and receives an endless drive belt 49 which may be driven by 10 any suitable source of power, but which is here shown as embracing a pulley 50 on the shaft of an electric motor 51 mounted on the base 1.

The carrier support 32 is also provided with a downwardly directed annulus 53 and with a 15 downwardly directed lip 54 forming a part of its outer flange 35, said annulus 53 and the lip 54 being provided with recesses for the reception of pairs of anti-friction bearings within which turn carrier drive shafts 55 (Figs. 3 and 6). These 20 drive shafts, as illustrated in Fig. 6, radiate from the axis of the machine, being spaced substantially equal distances apart circumferentially of the machine. The machine is illustrated as having sixteen such carrier drive shafts. It is to 25 be understood, however, that the number of these drive shafts may be varied as circumstances may indicate to be desirable. Each of these carrier drive shafts is furnished at its inner end with a pinion 56, all of such pinions constantly meshing 30 with the driving gear 26 above referred to. At the outer end of each shaft 55 there is secured a carrier driving pinion 57, the purpose of which is hereinafter more fully described.

Each of the carriers C (Fig. 9) comprises an 35 open rigid frame 58 provided at its inner end with anti-friction bearings for a guide roll 59 (Figs. 2 and 3) turning in a horizontal plane and which runs in the guide groove 38 of the ring 37. At its outer end each of the carriers C is furnished 40 with a pair of rolls 60 also turning in a horizontal plane and which run in the guide groove 36 of the upstanding flange 35 of the carrier support 32. These rolls 60 bear against the substantially vertical outer wall of the groove 36 and thus 45 oppose the centrifugal force which tends to cause the carriers to bear with substantial pressure against the flange 35. At the same time, the upper walls of the grooves 36 and 38 so confine the carrier rolls 59 and 60 that the carriers are 50 constrained to follow a plane circular path regardless of the stresses to which they may be subjected during operation. In order to support the weight of the outer ends of the carriers, they are provided with anti-friction rolls 61 turning on 55 substantially horizontal axes, said rolls 61 running on the lower horizontal wall of the guide groove 36.

Each carrier is furnished with a segmental gear rack 62 which is of such length as always to mesh 60 with at least one of the driving pinions 57. The length of the rack is such that several teeth of the rack are still in position for operative engagement with one of the pinions 57 when the advancing end of the rack comes into engagement 65 with the driving pinion of the next successive drive shaft 55, so that the carriers are always under positive control and can neither move forwardly nor backwardly at a speed different from that imposed by the drive pinions 57. However, 70 these racks are short enough so that there is always a space between the ends of successive carrier racks through which the strands from the other series of carriers may pass during the operation of the machine as hereinafter described.

75 The frame of each of the carriers C is provided

with bearing supports for the reception of the shaft or spindle 63 of a strand-supporting spool or bobbin 64 (Fig. 4) upon which the strand material may be wound. Each carrier is also furnished with strand tensioning means 65 (Fig. 5) such, for example, as spring fingers which rest upon the mass of strand material on the spool and which exert a substantially uniform tensioning effect upon the strand material as the latter is drawn off from the spool. Such a tensioning 10 means is more fully disclosed in the patent to Petersen No. 1,526,087, dated February 10, 1925. Each carrier also preferably is furnished with a detector finger 66 (Figs. 2 and 3) designed to respond to exhaustion of the strand material 15 from the bobbin and thereby to actuate stop mechanism hereinafter more fully described. The detector or feeler finger 66 preferably is secured to a shaft 67 (Figs. 2 and 9) mounted in bearings in the carrier frame so as to lie substantially parallel to the bobbin spindle, such shaft being provided with a coil spring 68 so designed as to tend to turn the detector finger 66 in a clockwise direction as viewed in Fig. 3.

Mounted upon the upper edge of the rim 35 25 of the carrier support is a second set of carriers D. Each of these carriers preferably comprises a frame 69 having spaced end members 70 and 70^a (Figs. 3 and 5), each of said end members having an open ended slot or recess 71 for the 30 reception of a spindle or shaft upon which is mounted a spool or bobbin 73 designed to hold the strand material, these bobbins or spools being like the bobbins 64 above described, if desired. For retaining the bobbin spindles in position, 35 each of the end members 70 and 70^a of the frame preferably has secured thereto a substantially flat or leaf spring 74 fixedly attached at its end 75 to the corresponding member of the frame and extending substantially in alignment with 40 the depth of the slot 71 with its free end directed toward the slot. At its free end each spring is 45 preferably furnished with a gate member or abutment 76 which normally stands opposite to and substantially closes the entrance to the corresponding slot 71. Since these springs extend in the direction of the depth of the slot, each spring normally forms a substantially rigid abutment preventing accidental escape of the bobbin spindle from the slots 71, but by bending the spring 50 downwardly, the entrance to the slot is left freely open so that the bobbin spindle may readily be removed. It is to be understood that the carriers C of the other set may be furnished with bobbin holding and retaining devices similar to 55 those just described.

Each of the carriers D is also preferably furnished with a detector or feeler comprising a shaft 78 (Figs. 2 and 5) having a spring 80 which tends to turn the finger 79 upwardly or counter-clockwise as viewed in Fig. 5. The finger 79 is 60 designed normally to engage the strand material wound upon the spool 73, such detector co-operating with the stop mechanism as hereinabove more fully described.

The frame of the carrier D is furnished with 65 upwardly directed members 81 and 81^a, respectively (Fig. 3), providing bearings for a strand guiding roll 82. The axis of this roll preferably is parallel to that of the spool 73 and the roll 70 is of more or less barrel shape, that is to say, it is crowned or convex in longitudinal cross section, whereby strand material from the spool, 75 passing over this roll under tension, tends always to move toward the central portion of the roll 75

and to leave the roll from substantially the same point, regardless of whether the strand is drawn off from the end of the spool or from the central part of the latter.

5 The flange 35 of the carrier support 32 is provided with a plurality of brackets 83 (Figs. 2 and 3) spaced at uniform distances apart about its circumference, such brackets being provided with bearings for shafts 83^a (Fig. 3) which form 10 pivotal supports or fulcrums for strand guiding levers 84. These shafts 83^a are inclined upwardly and inwardly so that their axes converge substantially at the braiding point, the parts preferably being so arranged that the axis of any one 15 of the shafts 84, thus extended, intersects the circular path in which the axes of the spools 64 of the carriers C travel. Thus the extended axes of the shafts 84 make an angle of the order of 8° with a plane perpendicular to the axis of the 20 machine.

Adjacent to each bracket 83, a second bracket 85 (Fig. 2) is secured to the flange 35 of the carrier support, and each of these brackets 85 is provided with a stub shaft on which turns a strand 25 guiding pulley 86. These stub shafts are so arranged that the pulleys 86 turn in planes which are substantially parallel to the axes of the guide rolls 82 and are so disposed that strand material, leaving from a point near the center of a 30 guide roll 82 of a given carrier D, is delivered tangentially from the roll 82 into the plane of the corresponding pulley 86, it being noted that the carriers D are not disposed radially of the machine, but are so arranged that the axis of 35 each roll 82 is in a vertical plane parallel to the vertical plane of the face of the corresponding pulley 86, while the groove in the pulley 86 is in a vertical plane substantially tangent to the surface of the roll 82.

40 Each of the strand guide levers 84 is furnished at an intermediate point with a cam follower (not shown) which runs in the cam groove 10, and is provided near its free end with a strand guiding pulley 87, preferably turning on anti-friction bearings and with its axis substantially 45 perpendicular to the axis of the corresponding shaft 83^a. The pulleys 87 are so arranged, relatively to the corresponding pulleys 86, that strand material leaving the pulley 86 will extend in a straight line into the plane of the pulley 87. The flange 35 of the carrier support is furnished with slots 88 (Fig. 2) and the ring 37 is furnished with corresponding slots 89 radially aligned with the slots 88 and so disposed that 50 strand material, leaving one of the pulleys 87, 55 may pass radially inward toward the braiding point through the slots 88 and 89 without contact with the flange 35 or the ring 37.

In accordance with the present invention, the 60 braided material which forms at the braiding point is drawn upwardly through the braiding die and through the tubular support 16 and is tensioned by passing over a take-up drum 90 (Fig. 1). This drum 90 is mounted to turn on a shaft 91 carried by a bracket 92 supported 65 by the bridge member 13, the drum having secured thereto a gear 93 which meshes with a gear 94 fast to a drum turning on a shaft mounted in bearings in a bracket 95 depending from the bridge member 13. The gear 94, in turn, 70 meshes with a gear 96 fast to a drum turning on a shaft carried by a bracket 97 mounted on the bridge member 13, the gears 93, 94, and 96 all being of the same diameter. The gear 96 75 meshes with a small pinion 98 on a shaft, also

supported by the bridge member, to which is secured a sprocket wheel 99 about which passes an endless sprocket chain 100. This sprocket chain leads downwardly toward the base of the machine where it passes around a second 5 sprocket wheel 101 mounted on a shaft 102 (Fig. 1) turning in a bracket 103 (Fig. 7) secured to the base member 1. A gear 104 is fixed to the shaft 102 and meshes with a gear 105 turning on a stud carried by an arm 106 arranged to 10 swing about the axis of the shaft 102. This gear 105 meshes with a gear 107 (Fig. 1) on a shaft 108 turning in bearings in the bracket 103, the gear 107 being a change gear and being splined to the shaft so that it may readily be removed 15 and exchanged for a gear of different pitch diameter, the mounting of the gear 105 on the arm 106 permitting such exchange of gears at will. On the shaft 108 (Fig. 7) is fixed a worm gear 109 which meshes with a worm 110 on a vertical 20 shaft 111 to which is secured a sprocket wheel 112 about which passes a sprocket chain 113 engaging a sprocket wheel 114 (Fig. 1) on the shaft 43. Thus the take-up drum is positively driven 25 at a definite speed ratio relatively to the speed of the carrier driving mechanism above described.

Referring to Fig. 4, which as above noted illustrates one of the strand carrying spools or bobbins, it is preferred to employ a spool having a barrel 64^a of substantial diameter, with a spindle 30 extending axially from end to end of the barrel although, if preferred, this spindle may take the form of short trunnions projecting from the ends of the barrel. Preferably the spool also has disk-like heads 64^b at its ends, although it is to be 35 understood that for certain purposes the strand may be wound upon a barrel or core unprovided with heads.

Preferably the barrel is provided with a slot or groove 115 at a point substantially midway its 40 ends, although the exact location is not important. This groove or slot is inclined and of more or less helical form, the inclination or slope of the helix being such that when strand material is wound upon the barrel, according to the chosen 45 method of winding, the wrappings of the strand which lie in contact with the barrel will bridge the slot or recess 115, the pitch of the windings of the strand being substantially different from the slope of the slot. This slot or recess 115 is 50 designed to receive the end of the feeler or detector finger above referred to, when the strand material is exhausted from the bobbin barrel and thus no longer bridges the recess 115.

Referring to Fig. 5, in which the detector device for one of the carriers D is more specifically illustrated, it may be noted that the shaft 78, which carries the detector or feeler finger 79, is furnished with an arm 116 disposed at the outer side of the carrier frame. This arm is arranged 60 to swing in the plane of a normally upstanding arm 117 of a bell crank lever mounted to turn on a stub shaft 117^a projecting from the end of the frame and having a second arm 118 which projects outwardly beyond the flange 35 of the carrier support. As above referred to, a spring 80 on the shaft 78 of the feeler device tends to swing the feeler 79 upwardly or in a counterclockwise direction as viewed in Fig. 5, such upward movement normally being prevented by engagement of the end of the feeler with the wrappings of strand material on the barrel. However, when the strand material is exhausted, the end of the feeler moves into the slot 115 and the shaft 78 turns and brings the arm 116 into contact with 75

the arm 117 of the bell crank lever, thus rocking the latter and lifting the arm 118 into the path of the stop motion mechanism about to be described.

Referring to Figs. 3 and 8, this stop mechanism preferably comprises an actuator including a normally downwardly directed arm 119 and a substantially horizontal shaft 119^a mounted in bearings in a bracket 120 carried by a support 121 which is conveniently fixed to the post 12. The support 121 (Fig. 8) is furnished with upstanding bearing members for a shaft 122 on which is mounted a rocker 123. This rocker is furnished with oppositely directed stop lugs 124 and 124^a for limiting its swinging movement and, if desired, may be furnished with a handle 128^a at its upper end whereby it may be manually actuated.

At its outer end the shaft member 119^a is furnished with a downwardly directed arm 125 (Fig. 8) having a pin 126 which is disposed between a pair of spaced, upstanding spring arms 127 and 127^a, respectively, which tend to hold the pin 126 at a central normal position with the arm 119 substantially vertical.

Between the arm 125 and the bearing in which the shaft 119^a turns, the shaft is furnished with a normally vertical flat portion which normally engages the hook-like end 128 of a latch 129 pivotally secured at 130 to the rocker 123. A spring 122^a (Fig. 8) embraces the shaft 122 and tends to swing the rocker 123 in a counterclockwise direction as viewed in Fig. 8, but such movement is normally opposed by the engagement of the end 128 of the latch with the flat face of the shaft 119^a. However, if the shaft be rocked, even to a slight extent, the flat face of the shaft acts as a cam to lift the latch 129, thus releasing it and allowing the rocker 123 to swing to the left (Fig. 8). When the rocker 123 thus swings, a toe member 131, carried by the rocker, is brought into engagement with a circuit breaking lever 132 which, upon being lifted, breaks an electrical circuit comprising the conductors 133 and 134 which supply current to the motor 51.

Referring to Fig. 3, the numeral 135 designates a lever arm which is normally substantially vertical and just within the inner surface of the flange 35 of the carrier support. This lever arm is mounted upon a shaft 136 arranged to turn freely in a bearing carried by the flange 35, the shaft having an arm 137 (Fig. 2) normally disposed in a more or less horizontal plane and in such a position that as the carrier support revolves, the arm passes beneath the depending stop motion lever arm 119.

As above described, each of the carriers C is furnished with a detector or feeler finger 66 and, it being understood that the spools employed in both the carriers D and C are of substantially the same type and all provided with the detector slots 115 or their equivalent, it will be evident that when the strand material is exhausted from the spool of one of the carriers C the corresponding detector finger 66 will be urged by the spring 68 in a downward direction thereby lifting an outwardly projecting tail portion 66^a (Fig. 2) of the detector finger. When this tail portion is so lifted, it will be brought into contact with the arm 135, as the carrier C revolves in its orbit, thus turning the arm 135 and swinging the arm 137 into an upright position so that it will contact the arm 119 of the stop motion mechanism as the carrier support 35 rotates, thus swinging the arm 119 and releasing the latch 129 thereby

stopping the machine. A suitable spring is arranged to return the shaft 136 to its normal position after it has thus been actuated by one of the detector fingers.

As above noted, when the strand material is exhausted from one of the spools of the carriers D, the corresponding lever arm 118 is lifted into the plane of the lever 119, so that as the carrier support 35 rotates, the arm 118 will strike the arm 119, thus also releasing the latch 129 to stop the machine.

The braided material is drawn off by the take-up drums in an upward direction from the braiding point at the lower end of the die 17 and the die is so located that strand material from the carriers C extends in a free unobstructed run without contact with any other mechanical part from its point of tangency with the strand mass on the bobbin to the braiding point. This straight, unobstructed run preferably makes an angle of approximately 8° with the horizontal, that is to say, approximately 98° with the axis of the formed braid as the latter is drawn off by the take-up. While this angle may doubtless be varied to a certain extent, I believe that the use of this angle produces the best results. It has been found after much experiment, that if the strands from the carriers C are thus permitted to extend in free runs out of contact with any mechanical part which might deflect them or impart frictional resistance and at an angle of the order of 8° as they approach the braiding point, it is possible to braid the material much more closely and to form a more dense braided structure than has heretofore been thought possible. It is further to be noted that this is accomplished without recourse to any guiding elements adjacent the braiding point or to the use of such devices as beaters or the like designed to compact the material.

In a copending application it has been described how strand material, such for example as resilient steel ribbon, may be braided to form a tubular braid wherein the interstices between the strands at their crossing points are extremely small, for example, of the order of $\frac{1}{1000}$ of an inch in area, and such that the tubular braided sheath thus made will successfully support a lining of rubber or the like against an internal pressure of the order of 20,000 pounds per square inch. The present machine is eminently well suited for making such a metallic tube and has been successfully used for this purpose, but it is likewise well adapted for braiding other materials than steel ribbon whereby to produce a braided structure which is extremely dense and close. In referring to metal ribbon, it is intended to include under this term a flat ribbon-like strand whether integral, that is to say, of one piece of metal, or formed of a plurality of fine wires, for example, laid side by side in the same plane so as collectively to form a ribbon-like strand.

In the above referred to copending application one theory of operation has been suggested to account for this extreme density of material when the carriers and the braiding point are arranged as above suggested, but whether or not this theory is the correct one, it is nevertheless true that the mechanism here mentioned is capable of producing braid having the characteristics mentioned. It is further to be noted that the various stresses acting on the carriers of the set C are adequately met by the means provided for guiding and supporting these carriers and that every provision has been made for reducing fric-

tion to a minimum, this being of great importance when the machine is designed for the braiding of heavy materials where the machine must necessarily be of large diameter and where the weight of the carriers and the material upon the bobbins is so large that centrifugal force is an important factor to be considered in the machine design.

In the machine as above described, the ratio of the speeds of the shafts 43 and 47 is as 1:2½ and the pitch diameters of the gears 26, 41 and 56 are so chosen that while the carrier support 35 turns in one direction at a given predetermined angular velocity, the carriers C are impelled in the opposite direction along the guide grooves 36 and 39 at substantially the same absolute angular velocity. Since these carriers C are positively controlled as to their movements by the engaging rack segments 62 and the drive pinions 57, they are caused to move at an exact predetermined angular velocity so that no matter how heavy the bobbin or what the tension imposed upon the strand material, the movement of the carriers of the two sets C and D will always be properly correlated and the strands of the two sets will meet at the braiding point always at the same angles of intersection.

In Figs. 10 and 11 other modes of supporting the carriers C are illustrated, these arrangements being such as more fully described in Petersen Patent No. 1,796,938 above referred to, the parts 35^x, 35^y; 38^x, 38^y; 9^x and 9^y, corresponding to the parts 35, 38 and 9 above described.

In the above description reference has at times been made to the axis of the machine as "vertical" and the position of parts relative to this axis has been described with respect to such a vertical axis. However, it is to be noted that by reason of the mounting of the carriers C it is possible to operate the machine with its axis in any desired position, for example, horizontal, such position sometimes being desirable if the machine be intended for covering a core material which is stiff or intractable and difficult to draw upwardly in a vertical direction.

As above noted, the shaft 18 which supports the rotating parts of the machine preferably is hollow and designed to accommodate core material T (Fig. 1) which may be drawn off from any suitable source of supply such, for example, as a spool or bobbin S, it being understood that any number of independent core strands may be supplied, as desired.

While certain desirable embodiments of the invention have been suggested and while materials suitable for the purpose have been mentioned, and while certain relative arrangements of parts have been specifically described by way of illustration, it is to be understood that the invention is not necessarily limited to the precise details but is to be regarded as broadly inclusive of all equivalents which fall within the scope of the annexed claims.

I claim:

1. In a braiding machine of the kind wherein carriers revolve in a circular orbit about the axis of a braiding die, a rotary support having concentric annular guideways for the carriers, each carrier having anti-friction rolls engaging the respective guideways, a segmental rack secured to each carrier, said support also having bearings for a plurality of radially extending carrier drive shafts, carrier drive shafts arranged to turn in said bearings, said shafts each having a carrier drive pinion constructed and arranged to mesh with the segmental racks secured to the respec-

tive carriers, a drive gear coaxial with the carrier support but independent thereof and arranged to mesh with pinions mounted on the several carrier drive shafts, and means for turning the support and drive gear in the same direction at such predetermined relative rates that the carriers are positively revolved in one direction and the carrier support turns in the opposite direction at substantially the same angular velocity.

2. In a braiding machine of the kind in which a rotary annular carrier support has bobbin carriers fixed thereto, and means defining a pair of radially spaced opposed coaxial grooves adapted respectively to receive the inner and outer ends of bobbin carriers, carriers movable along said grooves, means for impelling said carriers along the grooves comprising a drive gear coaxial with the support, an annular gear of larger diameter secured to the drive gear, a second annular gear of the same diameter as the latter secured to the carrier supporting annulus, and means for turning said annular gears at an accurately predetermined angular velocity.

3. In a braiding machine of the kind in which a rotary annular carrier support has bobbin carriers fixed thereto, and means defining a pair of radially spaced opposed coaxial grooves adapted respectively to receive the inner and outer ends of bobbin carriers, carriers movable along said grooves, each said carrier having a segmental rack secured thereto, bearings supporting a plurality of radial carrier drive shafts disposed below the path of the movable carriers and each having a pair of pinions, one pinion of each pair being arranged for engagement with the carrier racks, a drive gear coaxial with the annular support and always meshing with the other pinion of each pair, annular gears secured to the annular support and to said drive gear respectively, pinions meshing with said annular gears, shafts on which said pinions are mounted, and positive drive connections between said shafts operative to turn them at a constant predetermined angular velocity.

4. A braiding machine of the class described, comprising a rotary support and means for rotating it, two sets of bobbin carriers mounted on the support, the carriers of one set being fixed to the support, the support being provided with radially spaced coaxial guides defining an annular path for the bobbin carriers of the other set, driving means for the carriers of said latter set including a gear segment on each carrier and a series of radially arranged drive shafts mounted in bearings carried by the support, an annular gear coaxial with the support, pinions upon the several drive shafts which always mesh with said gear, and means for turning the annular gear at an angular velocity such that the carriers of the last-named set revolve oppositely to the carrier support and at substantially the same angular velocity as the latter.

5. A braiding machine of the kind in which a rotary support, carrying a series of bobbin carriers, is provided with means defining a pair of radially spaced coaxial guideways, a second series of carriers disposed between said guideways and each having supporting elements at its inner and outer ends which engage the inner and outer guideways respectively, each of said latter carriers having a segmental rack, the support having bearings for a series of radial drive shafts, a pinion on each shaft for engagement with the carrier racks, a gear coaxial with the support

but independent of the latter, pinions upon the several drive shafts which always mesh with said gear, and means for relatively turning the support and gear at such angular velocities as to cause the carriers to move along the guideway with an angular velocity equal to that of the angular support but in the opposite direction.

6. In a braiding machine of the kind wherein two sets of bobbin carriers revolve in circular orbits in relatively opposite directions about a common axis and in which cam-actuated strand guiding levers so position the strands from the carriers of one set that the carriers of the second set pass alternately over and under strands from the first set, in combination, a rotatable support comprising an annular rim upon which the carriers of the first set are fixedly secured, pivotal means, mounted upon the outer side of said rim, for the strand guide levers, said rim having a circumferential groove in its inner surface for guiding the outer ends of the carriers of the second set, a ring normally fixed to the support and having a circumferentially extending groove for guiding the inner ends of the carriers of the latter set, the rim and ring having slots for the passage of the strands from the carriers of the first set, said ring having arcuate grooves for the reception of bolts uniting it to the support and permitting circumferential adjustment of the ring relatively to the support, pairs of radially spaced bearings carried by the support, a carrier drive shaft turning in each pair of bearings, each shaft having a pinion at its outer end for engagement with racks secured to the carriers of the latter set, drive pinions at the inner ends of said shafts, a gear which meshes with the latter drive pinions, and means for relatively turning the support and gear in the same direction but at different angular velocities.

7. In a braiding machine of the kind in which two sets of bobbin carriers relatively revolve in opposite directions about a common axis, one set of carriers being affixed to a rotating annulus carrying pivotally supported strand guiding levers, one for each of its carriers, a braiding die defining the braiding point, and means supporting the other set of carriers to move in a circular orbit in a plane below that of the braiding point, characterized in that each of the guide levers swings about an axis making an angle of the order of 8° with the vertical and which substantially intersects the braiding point and carries a freely rotatable strand guide pulley adjacent to its free end, said pulley turning about an axis substantially perpendicular to that of the lever, and means operative to lead a strand from the corresponding carrier to said guide pulley.

8. In a braiding machine for braiding flat ribbon-like strands and wherein two sets of bobbin carriers revolve in circular orbits in relatively opposite directions about a common axis and in which cam-actuated strand guiding levers so position the strands from the carriers of one set that the carriers of the other set pass alternately over and under strands from the first set, and wherein a rotary support for one set of carriers has elongate slots for the passage of the strands from said carriers, in combination, an anti-friction guide pulley adjacent to the end of each strand guiding lever, each guide pulley having a substantially flat peripheral face of a width sufficient to accommodate the flat strand material and each such pulley being so arranged that a strand from the corresponding carrier, passing about the flat face of said anti-friction guide

pulley, is directed in a substantially radial path through the corresponding slot in the support.

9. In a braiding machine of the kind wherein two sets of bobbin carriers revolve in circular orbits in relatively opposite directions about a common axis and in which cam-actuated strand guiding levers so position the strands from the carriers of one set that the carriers of the second set pass alternately over and under strands from the first set, in combination, a rotating support having an annular rim, means securing the carriers of one set to said rim, means pivotally attaching the guide levers to said rim, the rim having a circumferentially extending groove in its inner surface, a ring concentric with and adjustably attached to the support, said ring having a peripheral groove, the walls of said groove constituting guiding and retaining means for the carriers of the other set, the rim and ring having radially aligned slots for the passage of strands from the first set of carriers, and means for rotating the support.

10. In a braiding machine of the kind in which two sets of bobbin carriers relatively revolve in opposite directions about a common axis, one set of carriers being affixed to a rotating annulus carrying pivotally supported strand guiding levers, one for each of its carriers, and a strand guide adjacent to the fulcrum of each lever, characterized in that each of the latter carriers has a strand guiding roll which is so crowned that a strand passing over the roll on its way from the carrier to the corresponding strand guide tends always to leave the roll at approximately the same point.

11. In a braiding machine of the kind in which two sets of carriers for spool-like bobbins relatively revolve in opposite directions about a common axis, one set of carriers being affixed to a rotating annulus carrying pivotally supported strand guiding levers, one for each of its carriers, each of the guide levers being arranged to swing about an axis which substantially intersects the braiding point, characterized in that each guide lever has a strand guide pulley adjacent to its free end, a second guide pulley arranged adjacent to the fulcrum of each lever, and an elongate strand guiding roll mounted upon a corresponding carrier, said guiding roll being so constructed and arranged as always to deliver a strand from the carrier into the plane of said latter guide pulley regardless of where the strand leaves the bobbin.

12. In a braiding machine of the kind in which two sets of bobbin carriers relatively revolve in opposite directions about a common axis, one set of carriers being affixed to a rotating annulus carrying pivotally supported strand guiding levers, one for each of its carriers, and wherein a strand guide pulley is arranged adjacent to the fulcrum of each lever, characterized in that each carrier of the latter set has an elongate strand support and an elongate strand guide roll disposed with their axes substantially parallel, the guide roll being so constructed and arranged that the strand tends to leave the roll always at substantially the same point and substantially in the plane of rotation of the guide pulley regardless of where the strand leaves the support.

13. In a braiding machine of the kind in which two sets of bobbin carriers relatively revolve in opposite directions about a common axis, one set of carriers being affixed to a rotating annulus carrying pivotally supported strand guiding levers, one for each of its carriers, characterized

in that each of the latter carriers has a strand guiding roll of substantially barrel-shape over which the strand from the carrier passes on its way to the corresponding guide lever.

- 5 14. In a braiding machine of the kind in which two sets of bobbin carriers relatively revolve in opposite directions about a common axis, one set of carriers being affixed to a rotating annulus carrying pivotally supported strand guiding levers, one for each of its carriers, characterized in that each of the guide levers is arranged to swing about an axis which substantially intersects the axis of the machine at the braiding point, each lever having a strand guide pulley adjacent to its free end arranged to turn about an axis substantially perpendicular to that of the lever, a strand guide pulley adjacent to the fulcrum of each lever arranged to turn in a plane which is substantially tangent to the guide pulley at the end of the corresponding lever, and a freely rotatable strand guiding roll of substantially barrel-shape mounted upon the corresponding carrier with its axis in a plane substantially perpendicular to the axis of the last-named guide pulley and arranged to deliver a strand from the carrier into the plane of said last-named guide pulley.
- 10 15. In a braiding machine of the kind in which two sets of bobbin carriers relatively revolve in opposite directions about a common axis, one set of carriers being affixed to a rotating annulus carrying pivotally supported strand guiding levers, one for each of its carriers, characterized in that each of the guide levers is arranged to swing about an axis which makes an angle of the order of 98° with the axis of the machine and which passes through the braiding point, each lever having a strand guide pulley adjacent to its free end, each said pulley having a substantially flat face and turning about an axis substantially perpendicular to that of the lever, and a flat faced strand guide pulley adjacent to the fulcrum of each lever and arranged to turn upon a stub shaft projecting from the outer periphery of the annulus and at such an angle that the plane of the pulley is substantially tangent to the guide pulley at the end of the corresponding lever.
- 15 16. In a braiding machine of the kind in which two sets of bobbin carriers relatively revolve in opposite directions about a common axis, one set of carriers being affixed to a rotating annulus carrying pivotally supported strand guiding levers, one for each of its carriers, characterized in that each carrier of the last-named set has a strand guiding roll whose axis is in a plane substantially perpendicular to the axis of the corresponding guide pulley, said roll being so crowned that a strand from the carrier, in passing over the roll on its way to the guide pulley, tends always to leave the roll at substantially the same point.
- 20 17. In a braiding machine for braiding flat ribbon-like strand material and in which two sets of bobbin carriers relatively revolve in opposite directions about a common axis, one set of carriers being affixed to a rotating annulus carrying pivotally supported strand guiding levers, one for each of its carriers, characterized in that each of the guide levers is arranged to swing about an axis which makes an angle of the order of 98° with the axis of the machine and which passes through the braiding point, each lever having a strand guide pulley adjacent to its free end, each said pulley having a substantially flat face and turning about an axis substantially perpendicular to that of the lever, and a flat faced strand guide pulley adjacent to the fulcrum of each lever and arranged to turn upon a stub shaft projecting from the outer periphery of the annulus and at such an angle that the plane of the pulley is substantially tangent to the guide pulley at the end of the corresponding lever.
- 25 18. In a braiding machine for braiding flat ribbon-like strand material, said machine being of the kind wherein two sets of bobbin carriers revolve in circular orbits in relatively opposite directions about a common vertical axis, and in which cam-actuated strand guiding levers so position the strands from the carriers of one set that the carriers of the second set pass alternately over and under strands from the first set, each of the guide levers being arranged to swing about an axis which makes an angle of the order of 98° with the axis of the machine and which passes through the braiding point, a braiding die disposed above the plane of revolution of the second set, in combination, a carrier support for the carriers of both sets and for the strand guide levers, the support being so devised and arranged that strands from the second set of carriers move in a free and unobstructed path and out of contact with any mechanical element from the bobbin to the braiding die, said paths each making an angle of the order of 98° with the axis of the formed braid as the latter is drawn off through the braiding die.

substantially perpendicular to the axis of the machine, and an elongate crowned strand guide roll, the axes of the spool and roll being substantially parallel, the carrier being so disposed upon the annulus that the strand extending from the spool and over the roll leaves the latter substantially in the plane of rotation of the

5

- 30 19. In a braiding machine of the kind in which two sets of bobbin carriers relatively revolve in opposite directions about a common axis, one set of carriers being affixed to a rotating annulus carrying pivotally supported strand guiding levers, one for each of its carriers, and strand guiding pulleys each turning about an axis adjacent to the fulcrum of one of the levers respectively, characterized in that each carrier of the last-named set has a strand guiding roll whose axis is in a plane substantially perpendicular to the axis of the corresponding guide pulley, said roll being so crowned that a strand from the carrier, in passing over the roll on its way to the guide pulley, tends always to leave the roll at substantially the same point.
- 35 20. In a braiding machine of the kind in which two sets of bobbin carriers relatively revolve in opposite directions about a common axis, one set of carriers being affixed to a rotating annulus carrying pivotally supported strand guiding levers, one for each of its carriers, and wherein a strand guide pulley is arranged to turn about a stub shaft supported by the annulus at a point adjacent to the fulcrum of each lever, characterized in that each carrier comprises means for supporting an elongate spool for strand material, the axis of the spool being in a plane which is

30 21. In a braiding machine for braiding flat ribbon-like strand material, said machine being of the kind wherein two sets of bobbin carriers revolve in circular orbits in relatively opposite directions about a common vertical axis, and in which cam-actuated strand guiding levers so position the strands from the carriers of one set that the carriers of the second set pass alternately over and under strands from the first set, each of the guide levers being arranged to swing about an axis which makes an angle of the order of 98° with the axis of the machine and which passes through the braiding point, a braiding die disposed above the plane of revolution of the second set, in combination, a carrier support for the carriers of both sets and for the strand guide levers, the support being so devised and arranged that strands from the second set of carriers move in a free and unobstructed path and out of contact with any mechanical element from the bobbin to the braiding die, said paths each making an angle of the order of 98° with the axis of the formed braid as the latter is drawn off through the braiding die.

35 22. In a braiding machine for braiding flat ribbon-like strand material, said machine being of the kind wherein two sets of bobbin carriers revolve in circular orbits in relatively opposite directions about a common vertical axis, and in which cam-actuated strand guiding levers so position the strands from the carriers of one set that the carriers of the second set pass alternately over and under strands from the first set, each of the guide levers being arranged to swing about an axis which makes an angle of the order of 98° with the axis of the machine and which passes through the braiding point, a braiding die disposed above the plane of revolution of the second set, in combination, a carrier support for the carriers of both sets and for the strand guide levers, the support being so devised and arranged that strands from the second set of carriers move in a free and unobstructed path and out of contact with any mechanical element from the bobbin to the braiding die, said paths each making an angle of the order of 98° with the axis of the formed braid as the latter is drawn off through the braiding die.

40 23. In a braiding machine for braiding flat ribbon-like strand material, said machine being of the kind wherein two sets of bobbin carriers revolve in circular orbits in relatively opposite directions about a common vertical axis, and in which cam-actuated strand guiding levers so position the strands from the carriers of one set that the carriers of the second set pass alternately over and under strands from the first set, each of the guide levers being arranged to swing about an axis which makes an angle of the order of 98° with the axis of the machine and which passes through the braiding point, a braiding die disposed above the plane of revolution of the second set, in combination, a carrier support for the carriers of both sets and for the strand guide levers, the support being so devised and arranged that strands from the second set of carriers move in a free and unobstructed path and out of contact with any mechanical element from the bobbin to the braiding die, said paths each making an angle of the order of 98° with the axis of the formed braid as the latter is drawn off through the braiding die.

45 24. In a braiding machine for braiding flat ribbon-like strand material, said machine being of the kind wherein two sets of bobbin carriers revolve in circular orbits in relatively opposite directions about a common vertical axis, and in which cam-actuated strand guiding levers so position the strands from the carriers of one set that the carriers of the second set pass alternately over and under strands from the first set, each of the guide levers being arranged to swing about an axis which makes an angle of the order of 98° with the axis of the machine and which passes through the braiding point, a braiding die disposed above the plane of revolution of the second set, in combination, a carrier support for the carriers of both sets and for the strand guide levers, the support being so devised and arranged that strands from the second set of carriers move in a free and unobstructed path and out of contact with any mechanical element from the bobbin to the braiding die, said paths each making an angle of the order of 98° with the axis of the formed braid as the latter is drawn off through the braiding die.

50 25. In a braiding machine for braiding flat ribbon-like strand material, said machine being of the kind wherein two sets of bobbin carriers revolve in circular orbits in relatively opposite directions about a common vertical axis, and in which cam-actuated strand guiding levers so position the strands from the carriers of one set that the carriers of the second set pass alternately over and under strands from the first set, each of the guide levers being arranged to swing about an axis which makes an angle of the order of 98° with the axis of the machine and which passes through the braiding point, a braiding die disposed above the plane of revolution of the second set, in combination, a carrier support for the carriers of both sets and for the strand guide levers, the support being so devised and arranged that strands from the second set of carriers move in a free and unobstructed path and out of contact with any mechanical element from the bobbin to the braiding die, said paths each making an angle of the order of 98° with the axis of the formed braid as the latter is drawn off through the braiding die.
